 ware

Application February 20, 1947, Serial No. 729,688

4 Claims. (Cl. 123—117)

1

As is well recognized in this art, the spark timing has a major effect upon the efficiency of operation of a spark ignition engine. In order to obtain maximum power, ignition must occur before the compression stroke is completed, that is, before top dead center is arrived at by the piston, because the combustion process requires a finite time and it is desirable that the maximum pressure be developed in the cylinder before the expansion of the power stroke begins.

As will be seen later and as well known in this art, the higher the engine speeds, that is, the higher the linear velocity of the piston, the earlier must be the spark, in order that the combustion process have sufficient time to generate the maximum pressure by the time the piston reaches top dead center. The optimum position for the spark in relation to the stroke is determined by laboratory experimentation, as will be more fully set forth below.

The interval between the time of the spark and the arrival of the piston at top dead center is termed "the spark advance." The earlier the spark is generated in the compression stroke of the engine, the more advanced is the spark, and the nearer to the time of arrival of the piston at top dead center, the more retarded is the spark. The degree of spark advance may be measured in terms of the crank angle.

While the degree of spark advance is a function of engine speed, it is also a function of throttle position. Thus, at any engine speed the degree of spark advance desirable for part throttle operation is greater than that required for full throttle operation. The adjustment of the spark advance in a spark ignition engine is accomplished by adjusting the angular relation between the breaker cam and the breaker points. As is well known in this art, the distributor contains a cam shaft which is rotated usually at half engine speed. The cam shaft rotates a cam usually in the form of a nut with lobes equal in number to the number of cylinders fired by the distributor. Surrounding the cam shaft and concentric therewith is a non-rotating breaker plate upon which is mounted a breaker, the function of which is to open the circuit of the ignition system so that the condenser discharges across the cylinder plug points. The angular relationship between the breaker and the cam determines the point in the stroke of the piston when the breaker points will separate and the spark will jump.

The term "full load" refers to that load which is imposed upon the engine at full open throttle position at any given speed. In other words, it is

2

the maximum load which may be imposed upon an engine when the throttle is wide open in order that a particular chosen speed be maintained at a steady rate.

5 "Part load" or "load at part throttle position" is that load which at any given speed is tolerable at any throttle position less than full.

"Road load" is that load which is at part throttle position. "Road load" has become a rather

10 generally recognized term in this art to specify as standard a part load which corresponds to the load on an engine equivalent to that imposed by an automobile of medium weight with three people of average size when driving on a straight road without acceleration. This rather arbitrary loading corresponds to about a 35° throttle opening at speeds of about 3400 R. P. M. Road load may thus be stated as the load imposed on an engine operating at 3400 R. P. M. at sea level 15 with the throttle, for example, at 35° from fully closed. With such road load imposed on the engine, as the throttle is opened beyond 35° the engine speeds up under such constant road load, and as the throttle is closed the engine slows 20 down.

25 In order to determine the best spark position for all conditions of operation of the engine, the engine is tested under load either in a dynamometer or on the road and the spark is set manually by adjusting the breaker plate for all conditions of throttle position and speed to establish what is known as the ideal spark advance curves for full load and road load positions. If the spark is controlled to advance along these curves at full load and road load they will also be adequate at intermediate load conditions. Such curves and spark advance settings are hereafter referred to as ideal or optimum curves or settings.

30 During cranking and idling the spark for best 35 operation is retarded. When operating at road load, the spark should be advanced, the degree of advance being greater as the speed at road load operations is higher. As the throttle is opened wider to full throttle position for full load operations the spark is best retarded, but at full throttle operation the spark should be more advanced the higher the speed at full load, i. e., wide open 40 throttle.

45 Spark ignition internal combustion engines, particularly those used in the automotive field, have devices for automatically adjusting the spark advance in relation to engine speed and also in relation to the throttle position at such engine speed. One method employed is to attach the 50 cam to centrifugal weights which are rotated by

the cam shaft. As the engine speed increases the weights move out under centrifugal force and rotate the breaker cam relative to the drive shaft, thus advancing the spark. However, since at part throttle operation a greater spark advance at any engine speed is desirable than that for full throttle operation, it is desirable that the spark advance mechanism at part throttle operation advance the spark an amount in addition to that which is obtainable from the centrifugal spark advance mechanism. In one standard type of such device now employed the breaker plate is advanced above that obtainable from the centrifugal weight by means of a link connected to a pneumatically operated power means for actuating the link. This means is conventionally a diaphragm positioned in a chamber which is in turn connected to an orifice positioned at the throttle in the air fuel induction system.

In another form of such automatic spark advance, such as represented by the Vanderpoel and Ostling Patent No. 2,249,446, the centrifugal weights are omitted and the entire advance is pneumatically controlled.

In addition to the orifice positioned at the throttle, an orifice is placed either at the main carburetor venturi or at an auxiliary venturi, as described in the co-pending application Serial No. 694, 266, filed August 31, 1946, by Garth L. Young and William Ostling. A by-pass is provided between the two orifices which are in turn connected to the pneumatic power means, specifically the diaphragm chamber similar to that described above. If desired a check valve may be placed in this by-pass. With such an arrangement the centrifugal weights may be entirely omitted and the spark advance may be obtained entirely by the rotation of the breaker plate by means of a stem connected to the diaphragm in the diaphragm chamber.

With such an arrangement at idling position the throttle orifice is on the carburetor side of the throttle and the velocity is so low that the vacuum generated is low. It is insufficient to advance the spark. When the throttle is opened to part throttle position the throttle orifice is on the manifold side of the throttle and is subjected to the vacuum of the intake manifold but this vacuum is in part bled through the Venturi orifice which is, of course, at a higher pressure, i. e., lower vacuum, and this modifies the excessive vacuum thus created by the manifold and the spark is advanced. When the throttle is opened to full open position, such as in the full load operation, the manifold vacuum drops substantially and is at practically atmospheric, but due to the velocity of the gases through the venturi there is a vacuum at the Venturi orifice which prevents the spark from being retarded to the degree it would have been if it had only been subjected to the manifold vacuum.

By positioning the check valve when the pressure at the venturi is lower than at the throttle orifice, as it is in full throttle position, the check valve closes so that the vacuum generated at the venturi is not bled by the higher pressure in the manifold, and thus the advance of the spark is increased over that which would have been obtained if the check valve had not been present.

It is an object of my invention to improve the operation of such spark advance mechanisms.

As is generally well recognized in this art, with such devices the suction exerted at road load (part throttle operation) may be excessive,

especially at intermediate engine speed, and over advance the spark if the advance at full load is any where near that which is desired at full load.

Additionally, vacuums at road load in the diaphragm chamber, where the spark advance mechanism is employed with carburetors having but a throttle orifice and no Venturi orifice, fall rapidly as soon as engine speeds reach an upper limit, for example, about 1000 to 2000 R. P. M. 10 This causes a retardation of the spark, i. e., an insufficient advance at such engine speeds. In order to obviate these excessive high vacuums, especially at lower and intermediate speeds, speeds under road load conditions, auxiliary bleeds have been introduced to bleed down the vacuum attained at the throttle orifice.

The difficulty with such bleeds is that they are non-selective in that they bleed at all positions of the throttle at low and intermediate engine 20 speeds. Thus, while they will bleed the excessive vacuums at low engine speeds under road load conditions, they will also bleed the insufficient vacuums attained at high engine speeds under road load conditions.

25 In another form of such device, the bleed orifice is positioned in the throat of the main carburetor venturi as in the Vanderpoel-Ostling Patent No. 2,249,446 or in an auxiliary venturi as in the improved modifications of the Vanderpoel-Ostling type disclosed in the above co-pending application Serial No. 694,266.

The Vanderpoel-Ostling type of spark advance control avoids this excessive bleeding at high engine speeds by positioning the throttle orifice 35 bleed at the throat of the carburetor venturi so that the pressures created in the throat at the high engine speeds do not excessively bleed the suctions created at the throttle orifice at high engine speeds under road load operations. 40 Additionally a check valve may be introduced into the bleed by-pass to shut off the throttle orifice when the throttle opens so widely that the pressures at the throttle orifice are actually greater than at the Venturi orifice.

45 In this manner while the excessive vacuums at low engine speeds are bled down to prevent an over advance at low engine speeds, the pressures created at the throttle orifice at higher engine speeds are not bled down but the effective 50 suctions are actually higher than that occurring at the throttle orifice. But even with this type of bleed the suctions created at road load speeds may, for some engine designs, be excessive to give an over advance of the spark if the advance 55 at full load is of satisfactory character.

It is desirable that the automatic spark advance mechanism approximate as closely as possible the spark advance curve obtained both at full load and road load over all engine speeds under 60 laboratory conditions, i. e., the ideal or optimum spark advance curve.

In the case of the governor controlled spark advance of the prior art, this may be accomplished by adjusting the advance caused by the governor 65 with increase in engine speed and also by adjusting the retarding spring tension in order to determine the advance obtained by the vacuum. In this way the rate of advance with engine speed caused by the governor is controlled and the rate 70 of advance with increase in vacuum is also controlled. It is usually possible by these controls to establish the full load spark advance curve in close approximation to the ideal curve. However, the difficulty is much greater when the road load 75 advance curve is considered. Since the adjust-

ment of the size of the orifice at the throttle and also the magnitude of the spring tension affect the entire curve at all engine speeds and load, the curve obtained for advance at different engine speeds at road load conditions may be made to fit the ideal curve at some engine speeds, but it is usually impossible to fit it throughout the entire range of engine speeds. Thus, if it is made to fit the curve at high engine speed the spark is usually under advanced at all lower engine speeds, or if it is made to fit at lower engine speeds it is usually far over advanced at high engine speeds.

In the case of the Vanderpoel-Ostling type of spark advance control, the full load curve can be made to approximate the ideal curve by a proper choice of orifice sizes at the throttle and venturi and by a proper choice of the retarding spring tension. However, the advance resulting at road load is not thus readily adjusted to the ideal curve. If the full load curve is adjusted properly the road load curve is over advanced and although some adjustment of orifice size and spring tension can be made to obtain the ideal full load curve while fitting the road load curve at some restricted range of engine speeds, it will be found that the advance is either excessive or insufficient at other engine speeds at road load. The ideal road load curve may, for some engines, not be approximate at all engine speeds by such adjustments.

In the automatic spark advance mechanism and carburetor construction of my invention, I have overcome these difficulties and may obtain the desired full load advance curve and road load advance curve for spark ignition engines by providing auxiliary interconnected throttle orifices so positioned that as the throttle is opened to place an orifice on the manifold side of the throttle, auxiliary orifices are positioned on the carburetor side of the throttle. The vacuum generated at the throttle orifices by the manifold vacuum is modified by the higher pressure existing on the carburetor side of the throttle.

The high manifold vacuum thus exerted at such positions of the part open throttle is modified by the bleeding action caused by the secondary orifices which are placed on the carburetor side of the throttle. As the throttle is opened wider, a second orifice which theretofore had been on the carburetor side of the throttle is also placed on the manifold side of the throttle. However, a third orifice may be provided which would then remain on the carburetor side of the throttle and will bleed the high vacuum generated in the two orifices heretofore mentioned which had been displaced to the manifold side of the throttle, and then as the throttle is opened wider the third orifice is moved to the manifold side of the throttle and the high vacuum is then generated on all three orifices. However, a fourth and a fifth orifice may be provided to remain on the carburetor side of the throttle to continue the aforesaid action.

In order to attain this effect the orifices are positioned at spaced intervals in the wall of the air fuel conduit on the carburetor side of the throttle when in closed position and so spaced that when the throttle is opened to road load position, for example, about 30 to 60°, for example, 35°, at some selected high engine speeds, for example, above about 3400 R. P. M., the throttle orifices in the air fuel conduit are all on the manifold side of the throttle.

The spacing of the orifices from each other is such that as the throttle is opened from idling to road load position, the throttle sweeps over

the orifices in series, putting them serially on the manifold side of the throttle. In this latter position, the throttle orifices are all at substantially the same pressure and do not bleed each other and act as a single orifice in the same manner as they do at full load throttle position (wide open throttle).

In this way the high vacuum generated by the manifold vacuum is modified and reduced as the throttle is opened wider and wider with some of the throttle orifices on the carburetor side of the throttle. The result of this variation is that if the advance which would result from the manifold vacuum is too great at engine speeds where part throttle operation is employed, the bleeding action thus produced by the auxiliary orifices will cause a reduction in the spark advance. The result is a retardation of the spark over the advance which would have been attained.

In the case of the modification of the Vanderpoel-Ostling construction, according to my present invention the Venturi orifice is employed in addition to the multiple throttle orifices to cause a further bleed of the vacuum at low engine speed in addition to that caused by the throttle orifices which remain on the carburetor side of the throttle. When a check valve is employed in the Vanderpoel-Ostling by-pass and the check valve closes at high engine speeds at road load, all of the throttle orifices are cut off from the spark advance mechanism. These auxiliary throttle orifices in such case act to fit the resultant spark advance curve more closely to the ideal curve. Since at low engine speeds some of the auxiliary orifices are on the carburetor side of the throttle and at higher engine speeds the auxiliary orifices are placed on the manifold side of the throttle, their effect upon the advance at low engine speeds is greatest and their effect is minimized at the high engine speeds so that the curve may be made to fit at low engine speeds as well as at high engine speeds when the vacuum generated at the venturi is the dominating influence on the advance. The improvement of the present invention is thus particularly adapted to the Vanderpoel-Ostling type of spark advance mechanism in which a Venturi orifice is employed to also modify this effect of the throttle orifices. In such construction the Venturi orifice prevents the vacuum exerted on the diaphragm chamber from falling to too low a degree so that while the vacuum exerted at full load, wide open throttle operation is sufficient to give the desired advance, it will also be sufficient to give the desired advance at road load conditions but be over advanced at lower speeds at the same loading. In such cases the auxiliary throttle orifices will modify the effective suction to retard the spark at the lower speeds over the advance attainable when only one throttle orifice is employed in the Vanderpoel-Ostling construction.

The use of the auxiliary throttle orifices of my invention is thus particularly adapted to the spark advance devices such as the Vanderpoel-Ostling type (with or without check valves) where both a venturi and a throttle orifice are employed, in which devices the full load advance at all engine speeds and the road load advance at high engine speeds can be made to fit the desired advance at such engine speeds and in which, except for these auxiliary orifices, at part throttle operations at lower engine speeds, the spark would be over advanced.

In such cases the degree of over advance which would otherwise be obtained can be modified or

eliminated by the use of the auxiliary throttle orifices. These throttle orifices are positioned so that at full open throttle all of the throttle orifices are on the manifold side of the throttle. The throttle orifices are also on the manifold side of the throttle when it is in the position at road load necessary to give the upper engine speed selected for such throttle position at such road load.

When the throttle is at idling position all of such throttle orifices are on the carburetor side of the throttle. At all intermediate positions of the throttle some of the orifices are on the manifold side of the throttle and an orifice or orifices are on the carburetor side of the throttle. The result of this construction is that the auxiliary throttle orifices on the carburetor side of the throttle bleed the throttle orifices on the manifold side of the throttle at all positions of throttle opening under road load operations in which the engine speed is below a predetermined upper limit.

The greatest retard is attained at the lowest speeds. These orifices will also reduce the degree of retard as the speeds increase and will cause no additional retarding action over the effect of a single orifice at the high engine speeds but will all act together as a single throttle orifice.

This invention and the objectives thereof will be more fully understood by reference to the accompanying drawings, in which

Fig. 1 is a view partly in section of a carburetor construction of the Vanderpoel-Ostling type including the improvements of the present invention, and of a spark advance mechanism suitable for use in connection therewith;

Fig. 2 is a fragmentary view taken along line 2—2 of Fig. 1, showing the position of the throttle at idling;

Fig. 3 is a similar view with the throttle at part open position;

Fig. 4 is a similar view with the throttle opened further;

Fig. 5 is a view on line 5—5 of Fig. 1;

Fig. 6 is a modification of the throttle opening employing a slot;

Fig. 7 is a chart of the operations of the engine and spark advance employing my invention.

The carburetor 1 is connected as conventional to an air supply. Air passes through passageway 2 past fuel nozzle 3 in the venturi 4. The throttle 5 is positioned in the air fuel passageway 6. A bore forming chamber 7 is formed in the wall of the passageway 6 into which bore open a plurality of orifices formed in the wall of the passageway 6. Three in number, 8, 9, and 10, are shown, although I may employ two or more than three, as will be understood by those skilled in this art from the present description of my invention.

All of the orifices open into chamber 7. The position of the orifice 8, and therefore of 9 and 10, is such that when the throttle is in idling position, shown solid in Fig. 1, the orifices 8, 9, and 10 are on the Venturi side of the throttle. The distance between centers of the orifices 8, 9, and 10 measured parallel to, i. e., along the longitudinal axis of 6, is such as to place all of the orifices on the manifold side of the throttle when the throttle is in road load position as illustrated at 5'. The distance between centers of the orifices measured in a direction perpendicular to the axis of 6 is dictated by the necessity of leaving sufficient metal between the orifices and also by degree of bleed required at various

throttle openings. It will be observed that the closer the orifices 9 and 10 are placed to the axis of 6 when measured as a projection on the plane passed through the carburetor perpendicular to the pivotal axis of 5 (see Fig. 1) the less the throttle opening upon which they will be placed on the manifold side of the throttle.

The spacing of the orifices and their diameter will be further described in connection with the discussion of Fig. 7.

The chamber 7 is connected by by-pass 12 to the orifice 11 which is positioned at the throat of the venturi 4. The ball check valve 13 is positioned in line 12 and is held against the seat 15 by the spring 14, which is just sufficient to overcome gravity, and thus holds the ball 13 against its seat when pressure is equalized on both sides of the valve, i. e., in chamber 7 and at the orifice 11.

The by-pass 12 is connected to the pneumatically operated spark advance mechanism (of construction forming no part of my present invention) by line 16 which connects to chamber 17 in which is the diaphragm 18. Chamber 17 is at the vacuum generated by the carburetor. The chamber 19 underneath the diaphragm is at atmospheric pressure. The retarding spring 17' holds the diaphragm down and the mechanism in full retard. The advance is caused by the motion of the diaphragm which is connected by rod 20 to the breaker plate 21 carrying the circuit breaker 22 which cooperates with the breaker cam 23 rotated at half engine speed by the cam shaft 24. The plate 21 carries a hole 25 which cooperates with a pin 26 positioned on an angularly adjustable bracket in the case of the device whereby the initial advance setting, when vacuum in 17 is zero and the maximum permissible advance irrespective of the magnitude of the vacuum in 17, is obtained, as is conventional in this type of spark advance construction.

Referring to Fig. 7, line A gives the variation in vacuum (measured as the difference in pressure in inches of mercury between 17 and atmospheric) occurring on the vacuum side of the diaphragm chamber 17 for full load, i. e., wide open throttle operation at speeds ranging from 400 up to 3400 R. P. M. The consequent full load advance for a particular case, chosen to explain and illustrate the principles of my invention, is illustrated in B. The initial advance setting was at 5°, the vacuum being 0 at speeds up to 600 R. P. M. Since at full load operation, i. e., wide open throttle, the auxiliary orifices 8, 9, and 10 have substantially no differential effect upon the total vacuum, the full load advance is substantially the same where the auxiliary orifices 8, 9, and 10 are employed as when a single orifice of area approximately equal to the area of the throttle orifices 8, 9, and 10 is employed.

The effect of these auxiliary orifices 8, 9, and 10 upon the spark advance is, however, illustrated by reference to curves C and D. Curve C gives the vacuum in the diaphragm chamber 17 in the Vanderpoel-Ostling type of mechanism where only a single throttle orifice of the same character as 8 is employed. It will be observed that in the case illustrated this vacuum rises sharply from low speed up to 1400 R. P. M., this being in the region where the throttle is opened sufficiently to pass the throttle orifice from the carburetor side to the manifold side of the throttle.

The advance for the particular chosen case is shown in curve D. It will be seen that the advance is very rapid due to the rapidly increas-

ing vacuum in the same range previously referred to. This is primarily because the pressure at the Venturi orifice is insufficiently high to bleed the vacuum existing in the throttle orifices. The result is a very rapid and sharp advance. Since at speeds of about 1400 R. P. M. the throttle is sufficiently wide open so that the total vacuum no longer increases as rapidly as engine speed but flattens, as is evident from curve C, the rate of spark advance with increasing speed also diminishes until when at a speed of about 2150 R. P. M., when the vacuum in 17 is 9 inches, the advance of the plate 21 comes against the stop 25 at a spark advance of 50°. It is thus maintained at substantially the same point until a speed of about 3100 R. P. M. is obtained, during which period the vacuum is greater than 9 inches, as is seen from curve C. When the throttle has become so wide open at speeds above about 3200 R. P. M. the manifold pressure starts dropping sufficiently to cause the total vacuum in the diaphragm chamber to drop below 9 inches and the spark is retarded from 50 to 48° at 3400 R. P. M. It will be noted, however, that the vacuum peak is at speeds above about 2400 R. P. M. and that drop in vacuum at higher speeds is prevented from becoming excessively sharp, as would be the result if it were controlled entirely by the throttle orifice, because at this point the manifold pressure has become less than the pressure at the Venturi orifice and the check valve is closed. The vacuum is therefore controlled entirely by the Venturi orifice and is prevented from dropping to a low value, so that the spark advance is maintained at the high point indicated by curve D.

A reference to curve E will show, however, that in such case the spark is excessively advanced. Curve E represents the ideal advance curve, for the particularly chosen illustrative case, such as is obtained by manual adjustment under laboratory conditions, giving the ideal road load advance at various engine speeds. It will be observed that the spark advance, curve D, has been made to match the ideal advance curve at high engine speeds, but that it is over advanced at all other speeds. Curve B corresponds to the so-called ideal full load curve, showing that the tension of spring 17' and the orifices have been made to obtain the desired full load advance.

The effect of the auxiliary orifices 9 and 10 on the vacuum in 17 to correct the over advance at lower engine speeds is evident by reference to curve F. As the throttle moves from idling position to part throttle position at a speed of 1400 R. P. M. orifice 8 is placed on the manifold side of the throttle, while orifices 9 and 10 are on the carburetor side of the throttle, as is, of course, the Venturi orifice. The high vacuum of the manifold is not fully exerted underneath the valve 13, since it is modified by the higher pressure existing in the air fuel passage on the carburetor side of the throttle at orifices 9 and 10. Since, however, the total pressure thus effected in the chamber 7 is less than that exerted at the Venturi orifice 11, the valve 13 remains open. However, the net of this combination is to create a vacuum in the chamber 7 which is less than would have been exerted had only orifice 8 been employed, the other orifices 9 and 10 being omitted as in the original Ostling-Vanderpoel arrangement. The net vacuum thus produced in chamber 7 at 1400 R. P. M. is shown at curve F which shows that when this situation has oc-

curred at about 1400 R. P. M., the total vacuum is 2.5 inches as compared to 5.8 inches when only one throttle orifice has been employed. The advance resulting is 38° which corresponds to the ideal advance at such speed and throttle position, as given in curve E. As the throttle is opened wider the space between the periphery of the throttle and the conduit wall is increased and the vacuums at the throttle orifices rise due to increase in speed of the engine until at a speed of 2200 R. P. M. the throttle is opened sufficiently to place orifice 9 on the manifold side of the throttle, leaving only orifice 10 on the carburetor side of the throttle. Because of the bleeding effect of orifice 10, as well as that of the Venturi orifice 11, the vacuum generated in the chamber 17 is not as great as occurred in the original Vanderpoel-Ostling arrangement. As is seen from curve F, the vacuum thus generated at 2200 R. P. M. corresponds to 4.5 inches instead of 9.2 inches of mercury (curve C) and the advance thus obtained at this R. P. M. corresponds to 46.1°, and this will be seen to be the ideal advance at this speed (curve E). As the speed is increased by the further opening of the throttle at 3200 R. P. M., the third orifice 10 is now placed on the manifold side of the throttle. Therefore, since all three orifices are now on the manifold side of the throttle, the vacuum generated corresponds to that generated when only one orifice 8 is employed, i. e., 9 inches, and corresponds to 50°. The advance thus obtained is that obtained under the operation according to curve C which, it will be seen, is coincident with that of curve F. At this point the throttle is substantially at road load position, i. e., part throttle position and all of the throttle orifices 8, 9, and 10 are on the manifold side of the throttle. The curve F is shown dotted, indicating that the intervals between 4 and 1400 R. P. M. and between 1400 and 2200 R. P. M., and between 2400 and 3200 R. P. M. need not necessarily be a straight line as indicated on F. However, the advance curve obtained with the orifices 8, 9, and 10 fits the ideal curve at the speeds 1400, 2200 and 3200 R. P. M. and will fit quite closely at intermediate speeds.

It will thus be seen that where, as in the Vanderpoel-Ostling type of spark advance control, the advance is excessive at low engine speed and approximates more closely the desired advance at high engine speeds, I am able to modify the advance at low engine speeds without disturbing the advance at high engine speeds and thus am able to fit the advance to the ideal advance curve throughout the range of engine speeds without affecting the full load advance.

It will be recognized that since at full load the throttle is wide open all three orifices function in substantially the same way as a single orifice. The check valve, if one is employed, closes, as in the case of the Vanderpoel-Ostling device employing a check valve, permitting the full vacuum existing at the venturi to be exerted in the diaphragm chamber and to give the full load advance which is thus obtained with a single or a plural type of throttle orifice construction, i. e., the vacuum of line A and the advance of line B. In the case of the plural throttle orifices employed with a Vanderpoel-Ostling device without check valve, a similar action obtains.

By altering the size of the 2 orifices, their number and distribution at the throttle, the effect at various engine speeds at various throttle positions may be altered to modify the total vac-

11

uum generated at any engine speed at road load operation in the desired manner to fit the advance obtained to that desired. Thus, by providing a number of orifices at the throttle so that as the throttle is opened wider and wider the orifices are shifted from the carburetor side of the throttle to the manifold side of the throttle, the net vacuum existing in the diaphragm chamber may be controlled to the desired variation with engine speed to give the desired degree of advance with variation in engine speed at road load operations.

From what has been said above, it is apparent that the auxiliary orifices act to cause a retardation of the spark above that which is attainable with a single throttle orifice and their utility is therefore of primary value where the spark advance mechanism employing such throttle orifice causes an over advance of the spark at all engine speeds at road load below an upper engine speed at which the single orifice gives the desirable advance. Such a situation is particularly the case in the Vanderpoel-Ostling type of control mechanism for certain motor designs. In such construction the bleed of the single throttle orifice by means of the Venturi orifice is supplemented by the auxiliary throttle orifices which also bleed the manifold vacuum at throttle openings which are less than that setting required to obtain the aforementioned engine speed chosen as the definition of road load conditions.

In Fig. 6 is shown a slot which in effect is cut through the orifices 8, 9, and 10 and acts in the same manner as the auxiliary orifices 8, 9, and 10 except instead of the effect being discontinuous, represented by the stages of bleed as the throttle traverses each orifice serially, the bleed changes continuously as the proportion of the slot, on the manifold side of the throttle to that on the Venturi side of the throttle, changes as the throttle is opened wider and wider until at road load operation at high speeds all of the slot is on the manifold side of the throttle, whereas at idling speed the slot is entirely on the Venturi side of the throttle.

The specific values of the vacuums and advance as shown in Fig. 7 and as described in the specification discussing said figure, and the specific values of throttle position and speed and loading chosen to describe road load, are employed as illustrative only and not as a limitation of my invention. The specific values of the vacuums and of the advance and their variation with engine speed will vary with engine design and with the values of the throttle opening, speed and loading chosen as the definition of road load. The positioning of, sizes and number of throttle orifices which are desired will depend on the above factors and upon the specific nature of the carburetor construction. However, by applying the principles described above, those skilled in the art will be able to produce the desired spark advance variation with speed desired at full load and at that degree of loading (throttle position and speed) chosen as road load.

While I have described a particular embodiment of my invention for the purpose of illustration, it should be understood that various modifications and adaptations thereof may be made within the spirit of the invention as set forth in the appended claims.

I claim:

1. An automatic spark advance mechanism for spark ignition engines, comprising a carburetor including an air inlet and a fuel inlet to said car-

12

buretor, an air passageway, a venturi in said passageway, an orifice at said venturi, a throttle in said passageway, means for attaching said passageway to the intake manifold of a spark ignition engine, a plurality of orifices positioned in the wall of said passageway at said throttle, said orifices being disposed at said throttle longitudinally of the axis of said first mentioned passageway and spaced along said wall in relation to said throttle to be on the carburetor side of said throttle when said throttle is in idling position and all of said throttle orifices are on the manifold side of said throttle when said throttle is in road load position, at part open throttle at a predetermined upper engine speed, a conduit connecting said orifices at said throttle and said orifice at said venturi, and a tube for connecting said conduit to a pneumatic spark advance mechanism.

2. An automatic spark advance mechanism for spark ignition engines, comprising a carburetor including an air inlet and a fuel inlet to said carburetor, an air passageway, a venturi in said passageway, a throttle in said passageway, an orifice at said venturi, a conduit connected to said air passageway at said venturi and at said throttle, the connection at said throttle extending longitudinally of said passageway forming an inlet into said conduit at a plurality of points along said passageway said throttle being positioned in respect of said connection of said conduit at said throttle so that when the throttle is in closed position said last-named point of connection is between the throttle and the air inlet and when the throttle is in part open position the conduit is connected to the air passageway at a point between the throttle and the air inlet and also between the throttle and the intake manifold connection, a tube connected to said conduit and adapted for connection to a pneumatic spark advance mechanism.

3. An automatic spark advance mechanism for spark ignition engines, comprising a carburetor including an air inlet and a fuel inlet to said carburetor, an air passageway, a venturi in said passageway, an orifice at said venturi, a throttle in said passageway, means for attaching said passageway to the intake manifold of a spark ignition engine, a plurality of orifices positioned in the wall of said passageway at said throttle, said orifices being disposed at said throttle longitudinally of the axis of said first mentioned passageway and spaced along said wall in relation to said throttle to be on the carburetor side of said throttle when said throttle is in idling position and all of said throttle orifices are on the manifold side of said throttle when said throttle is in road load position, at part open throttle at a predetermined upper engine speed, a conduit connecting said orifices at the throttle and venturi, a tube adapted for connecting to a pneumatic spark advance mechanism connected to said conduit.

4. An automatic spark advance mechanism for spark ignition engines, comprising a carburetor including an air and fuel inlet to said carburetor, an air passageway, a venturi in said passageway, a throttle in said passageway, an orifice at said venturi, a conduit connected to said first passageway at said venturi and at said throttle, the connection at said throttle to said conduit extending longitudinally of said passageway to provide an elongated connection of said conduit to said passageway said throttle being positioned in respect of said throttle connection of said conduit so that when the throttle is in closed position said

last-named point of connection is between the throttle and the air inlet and when the throttle is in part open position the conduit is connected to the first passageway at a point between the throttle and the air inlet and also between the throttle and the intake manifold connection, a tube connected to said conduit and adapted for connection to a pneumatic spark advance.
